J. G. POORMAN

POULTRY HOVER

Filed Oct. 9, 1922

Fig. 4.

Inventor:

John G. Poormann,
By Dyerforth, Lee, Britton & Wiles,
Atty.

UNITED STATES PATENT OFFICE.

JOHN G. POORMAN, OF TINLEY PARK, ILLINOIS.

POULTRY HOVER.

Application filed October 9, 1922. Serial No. 593,266.

To all whom it may concern:

Be it known that I, JOHN G. POORMAN, a citizen of the United States, residing at Tinley Park, in the county of Cook and State of Illinois, have invented a new and useful Improvement in Poultry Hovers, of which the following is a specification.

My invention relates, particularly, to poultry hovers of a type involving the simulation of the condition presented by hens in the mothering of chicks and involving a housing structure containing a mass of feathers supported in depending condition and in such position that the feathers project to within a short distance of the bottom of the housing and partially envelop the chicks.

My primary object is to provide a novel, simple and inexpensive construction of hover of the type above referred to; to provide for proper ventilation thereof; and to provide, by a simple construction, a space into which the chicks may pass and be out of contact with the feathers.

Referring to the accompanying drawings: Figure 1 is a perspective view of the body portion of the frame or housing forming the hover. Figure 2 is a similar view of the front, removable, side of the hover. Figure 3 is a broken perspective view of the top of the hover and the part thereof which carries the feathers; and Figure 4, a section taken at the line 4 on Fig. 1 and viewed in the direction of the arrow, this view being taken through the construction in assembled condition.

The particular construction shown involves a pair of end boards 5 shown as arranged in spaced-apart parallel relation, a side board 6 connected at its ends with adjacent ends of the end boards 5, a removable front section 7, a cleat structure 8 connecting together the end boards 5 at their front ends, and a removable and replaceable top board 9. The cleat section 8 is shown as formed of two strips 10 and 11 secured together to extend at right angles to each other, the ends of the strip 10 being inset into the inner faces of the end boards 5 as shown. The section 11 extends forwardly from the lower edge of the section 10, the inner faces of the end boards 5 containing, coincident with the outer face of the cleat section 11, vertically-disposed grooves 12 adapted to receive the front sec-

tion 7 which is preferably made in the form of a frame with the opening provided therein covered with wire mesh, represented at 13, it being understood that the front side 7 is thus removable and replaceable relative to the body of the hover. The end boards 5 are each provided with cleats 14 which form supporting ledges for the top board 9 which latter is of such dimensions as to fairly snugly fit within the confines of the cleat section 10, rear side member 6 and end boards 5.

The mass of feathers to be dependingly supported in the housing for the purpose hereinabove set forth, are carried by the member 9, these feathers being shown as provided in bunches, represented at 15, and preferably extending at their lower ends in mutually overlapped relation to form a relatively compact and dense mass of feathers in such position as to extend down over the chicks located within the hover, the body of which is not shown as provided with any bottom but which may have a bottom board applied thereto if desired, these structures, however, being ordinarily without bottom boards and merely set down onto the ground when in use. The bunches 15 of feathers may be formed in any desirable way and likewise secured to the board 10 to depend therefrom, the feathers, by way of example, being provided in bunches held together in the same way that the feathers of the ordinary household feather duster are held together, and supported on the board 9 in the same way that the feather duster head is supported from the handle thereof.

Provision is made in the construction shown for the proper ventilation thereof, the top board 9 to this end being provided adjacent its rear edge with a slot 16 which extends substantially the entire length of the board 9, and at its front edge with a similar slot 17, but preferably of considerably greater width, which likewise extends substantially the entire length of the board 9, these slots being covered with wire mesh, as represented at 18 and 19.

Inasmuch as the bunches of feathers 15 do not extend materially beyond the front edge of the top board 9, there is thus provided between the mass of feathers and the front wall 17 a space which constitutes a runway into which the chicks may pass.

It will be readily understood from the foregoing that a hover constructed in accordance with my invention is not only a novel and simple construction but serves to 5 perform, in a highly satisfactory manner, the functions for which constructions of this general character are provided and affords great security against access of animals thereto.

10 While I have illustrated and described a particular construction embodying my invention, I do not wish to be understood as intending to limit it thereto as the same may be variously modified and altered without 15 departing from the spirit of my invention.

What I claim as new, and desire to secure by Letters Patent, is:

A poultry hover comprising a body formed of enclosing sides, and a top-portion 20 provided with feathers depending therefrom into the interior of said body and containing openings therethrough adjacent its front and rear edges for ventilation, the feathers depending from said top-portion stopping a sufficient distance from the front 25 edge of said top-portion to provide a runway between said feathers and the front of the structure.

JOHN G. POORMAN.
